UNITED STATES PATENT OFFICE.

WILLIAM ASHLEY KELLY, OF JERSEY CITY, NEW JERSEY, ASSIGNOR TO UNDERWOOD TYPEWRITER COMPANY, OF NEW YORK, N. Y., A CORPORATION OF DELAWARE.

INVOICE SHEET.

Application filed September 7, 1922. Serial No. 586,581.

To all whom it may concern:

Be it known that I, WILLIAM ASHLEY KELLY, a citizen of the United States, residing in Jersey City, in the county of Hudson and State of New Jersey, have invented certain new and useful Improvements in Invoice Sheets, of which the following is a specification.

This invention relates to a novel multiple-part entry-sheet, and its objects are symmetry of appearance, facility and convenience in use, and economy of paper. The novel entry-sheet may comprise a bill-part having detachably joined thereto, along lines of folding, a stub-part and a record-part, in such manner that these three joined parts produce a symmetrical rectangular entry-sheet, all of the parts of the entry-sheet being foldable along said lines into superimposed relation, so that, by means of interleaved carbon-sheets, all of the superimposed parts of said sheet may be typed at the same time and afterwards separated along said lines of folding. Each of said sheet-parts may have thereon a form comprising suitable item-designations to be brought into alignment when the entry-sheet is folded for typing, so that the items typed upon the superimposed portions of the sheet-parts will appear under the proper item-designations on each of the parts of the entry-sheet.

After the entry-sheet has been thus typed in its folded condition, the ledger-sheet or record-part can be detached and kept in the office, while the bill-part with its attached stub is sent to the customer, who detaches the stub-part from the bill-part, keeping the bill-part and returning the stub-part with his check.

Other features and advantages will hereinafter appear.

In the accompanying drawings,

Figure 1 is a plan view of one of the entry-sheets in flat condition, and shows the side thereof which bears the form or item-designations for the bill-part of the entry-sheet.

Figure 2 is a perspective view, showing one way of folding the entry-sheet to bring the three parts into superimposed relation, and shows the bill-part at the front, the ledger-sheet or record-part at the back, and the stub-part interposed between the bill-part and the record-part.

Figure 3 is a similar view, showing another way of folding the entry-sheet, and shows the ledger-sheet or record-part at the front, the bill-part at the back, and the stub-part interposed between the bill-part and the record-part, and also further shows, in broken lines, the stub-part as folded over at the back of the bill-part, to illustrate yet another way of folding the sheet.

The entry-sheet comprises a bill-part 1, which may be a statement or invoice, a stub-part 2 on the bill-part, and a record-part or ledger-sheet 3. The stub-part 2 is shown at the right side of the bill-part 1, and is detachably joined or connected therewith along a vertical line of folding 4, indicated in the drawings as a line of perforations. The stub-part 2 is of the same length, but is shown as of less width than the bill-part 1. The lower or bottom edge of the bill-part 1 and the adjacent portions of the lower edge of the record-part 3 are detachably joined or connected together along a transverse line of folding 5, indicated in the drawings as a line of perforations.

In the form of the invention shown in the drawings, the bill-part 1 and the record-part 3 are of the same length, but the record-part 3 is of greater width than the bill-part 1, so as to extend or project beyond the right side of the bill-part 1, this projecting portion of the record-part 3 being coterminous with but unconnected to the adjacent lower end of the stub-part 2, so that when the entry-sheet is flat, as shown, the record-part 3 will be equal in width to the combined widths of the bill-part 1 and its stub-part 2. The lower edge of the stub-part 2 is separated from the adjacent upper edge of the right-hand end portion or extension of the ledger-sheet 3, by means of a cut or slit, indicated in Figure 1 at 6.

Upon each of the sheet-parts at the top thereof there is an identifying designation shown in the drawings as "Bill" on the bill-part 1, "Stub" on the stub-part 2, and "Ledger-sheet" on the record-part 3. Each of the sheet-parts also bears on its front or face item-designations arranged transversely in columns, each column being provided with a proper heading. In the entry-sheet, shown in the drawings, the bill-part

1 is provided with seven item-designations for corresponding item-receiving columns, while the stub-part 2, which is of less width than the bill-part 1, is provided with only 5 three item-receiving columns and column-designations which correspond to the last three columns and column-designations on the bill-part 1.

The record-part or ledger-sheet 3 is provided with the same item-receiving columns and item-designations similarly arranged from left to right in reference to the bill-part 1, and also corresponding at the right to the item-receiving columns and column-designations on the stub-part 2. The record-sheet or ledger-sheet 3 is further provided, upon the extension at the right side thereof, with four additional column-designations and columns to receive additional 15 data which is to appear upon the ledger-sheet or record-part 3, but not upon the bill-part 1 nor upon the stub-part 2. If desired, this additional data, which is to appear on the record-part or ledger-sheet 20 3 only, may be typed thereon at the same time that the entry-sheet is typed in folded condition, or these additional items may be filled in upon the ledger-sheet at a later date. It will be noted that the stub-part 25 2 will contain information corresponding only to a part of the information which is typed upon the bill-part 1 and the record-part 3.

It is to be noted that the columns and 35 column-designations or item-designations on the bill-part 1 are upon one side of the entry-sheet, while the column and column-designations or item-designations for the stub-part 2 and for the record-part 3 are 40 upon the other side of the entry-sheet. It is also to be noted that the columns and column-designations on the stub-part 2 are in transverse alignment with the columns and column-designations on the bill-part 1, 45 and that the columns and column-designations on the stub-part 2 terminate at the same distance from the vertical line of perforations 4, as do the columns and column-designations on the bill-part 1, so that, when 50 the stub-part 2 is folded upon the bill-part 1, in either direction, along the perforated line 4, the columns and column-designations on the stub-part will be brought into register with the corresponding columns 55 and column-designations on the bill-part 1, as indicated in Figures 2 and 3. It is to be further noted that the item-receiving columns and column-designations on the bill-part 1 are in vertical alignment with the 60 corresponding columns and column-designations on the record-part or ledger-sheet 3, and that the column-designations on each of these sheet-parts are arranged at the same 65 distance from the tops or upper edges thereof, so that, when the record-part 3 is folded,

in either direction, upon the bill-part 1 along the transverse perforated line 5, as indicated in Figures 2 and 3, the columns and column-designations on the bill-part 1 will be brought into correct register with the corresponding columns and column-designations on the record-part or ledger-sheet 3, and, also, at the same time, obviously, the columns and column-designations on the folded stub-part 2 will be brought into 75 register with the corresponding columns and column-designations on the record-part or ledger-sheet 3, in the folded condition of the entry-sheet.

When the three sheet-parts are to be 80 folded into super-imposed relation for typing the folded entry-sheet, this folding may be done conveniently by first folding the stub-part 2 either forwardly, as in Figure 3, or backwardly, as in Figure 2, and, as 85 indicated in broken lines in Figure 3, upon the bill-part 1, and then, by folding the record-part or ledger-sheet 3 either forwardly, as in Figure 3, or backwardly, as in Figure 2, into superimposed relation with 90 the bill-part 1 and folded stub-part 2. When the entry-sheet is typed in its folded condition, all the items typed directly upon either the bill-part 1, as in Figure 2, or upon the record-part 3, as in Figure 95 3, will be reproduced upon the other of these two sheet-parts, and such items as are typed within the zone of the stub-part 2 will be reproduced upon that also.

The fact that, in any method of folding, the right-hand side extension of the ledger-sheet 3, together with the column-designations thereon, lies entirely at the outside of the vertical line of folding 4 between the bill-part 1 and its stub-part 105 2, will enable, while the folded sheet is still in the machine, the typing of any desired additional items on the record-part 3, which it is desired shall not appear upon the bill-part 1 nor upon the stub-part 2. 110

The entry-sheet of the present invention is economical of paper by reason of having no portions cut away and no projecting portions, and also by reason of having therein no large blank or unused spaces. 115 The entry-sheet of the present invention is not only of symmetrical shape as a whole, but it also remains in symmetrical shape after the detachment therefrom, in proper successive order, of each of the detachable 120 sheet-parts. Ordinarily, after typing, first the ledger-sheet 3 will be detached from the bill 1 along the transverse line of perforations 5, leaving the bill 1 and stub 2 attached and forming together a sheet of 125 symmetrical form. The ledger-sheet 3 will then be filed in the office, being provided for this purpose with a pair of large holes 7 in its upper margin. The attached bill 1 and its stub 2 would then be sent to the 130

customer, who would tear off the stub along the vertical line of perforations 4, and would retain the stub, containing the items of interest to him, and, accompanied by 5 his check, would return the bill 1, all the items of which have been duplicated on the ledger-sheet 3, which had been retained as a record in the office.

In making out successively a large number 10 of small bills, each containing only one line, or possibly two lines of writing, such as gas bills or electric bills, of which an example of the latter is shown in the drawings, the use of the multiple-part 15 entry-sheet of the present invention is a great convenience and saves much time.

This invention is in the nature of an improvement upon the features disclosed in the application of John A. Wherry, Serial No. 20 557,873, filed May 2, 1922.

Variations may be resorted to within the scope of the invention, and portions of the improvements may be used without others.

Having thus described my invention, I 25 claim:

1. A multiple-part entry-sheet of symmetrical substantially rectangular shape comprising a bill-part having suitable item-designations thereon, a lateral stub-part of 30 the same length as the bill-part and having one of its sides detachably joined along a vertical line of folding to one of the sides of the bill-part, and a record-part, having item-designations thereon corresponding 35 with the item-designations on the bill-part, detachably joined along a transverse line of folding to the corresponding end of the bill-part throughout the width of the latter, and having an extension coterminous with 40 but unconnected to the adjacent end of the stub-part, so that when the entry-sheet is flat the record-part will be equal in width to the combined widths of the bill-part and stub-part, the stub-part being foldable 45 along said vertical line of folding into superimposed relation with the bill-part, and the record-part being foldable along said transverse line of folding into superimposed relation with the bill-part and the folded 50 stub-part, but with said extension of the record-part projecting beyond the folded stub-part, so that all of said sheet-parts may be typed at the same time in their folded condition to reproduce corresponding 55 items upon their superimposed portions, and so that subsequently the record-part and the stub-part may be separately detached from the bill-part along said lines of folding.

2. A multiple-part entry-sheet of symmetrical substantially rectangular shape comprising a bill-part having suitable item-designations thereon, a lateral stub-part of 60 the same length as the bill-part and having one of its sides detachably joined along a

vertical line of folding to one of the sides of the bill-part and having item-designations thereon corresponding to the item-designations on the bill-part and in lateral alignment therewith, but on the opposite side of 70 the entry-sheet and in laterally reversed relation when the entry-sheet is flat, and a record-part detachably joined along a transverse line of folding to the corresponding end of the bill-part and having an extension 75 beyond the bill-part coterminous with but unconnected to the adjacent end of the stub-part, so that when the entry-sheet is flat the record-part will be equal in width to the combined widths of the bill-part and stub-part, the record-part having item-designations thereon corresponding with the item-designations on the bill-part, but on the opposite side of the entry-sheet when the entry-sheet is flat, the record-part also having 80 additional item-designations on its said extension, the stub-part being foldable along said vertical line of folding to bring the item-designations thereon into register with the corresponding item-designations on the bill-part, and the record-part being foldable 85 along said transverse line of folding to bring the item-designations thereon corresponding to those on the bill-part into register therewith and also into register 90 with the corresponding item-designations on the stub-part, but with the item-designating extension of the record-part projecting beyond the folded stub-part, so that when the entry-sheet is typed in its folded 95 condition all of the registering items will appear upon the respective superimposed sheet-parts, and so that subsequently the record-part and stub-part may be separately 100 detached from the bill-part along said lines 105 of folding.

3. A multiple-part entry-sheet of symmetrical substantially rectangular shape comprising a bill-part having a series of transversely arranged item-designations 110 thereon, a stub-part at the right side of the bill-part of the same length as the bill-part and detachably joined therewith along a vertical line of folding, the stub-part being of a width to have thereon a transverse series of item-designations corresponding to a desired number of the item-designations at the right side of the bill-part, and when the entry-sheet is flat the item-designations on the stub-part being in transverse alignment with but on the other side of the entry-sheet and in laterally reversed relation to the corresponding item-designations on the bill-part, the item-designations on the stub-part being brought into register with the corresponding item-designations on the bill-part when the stub-part is folded along 115 said vertical line into superimposed relation with the bill-part, and a record-part of the 120 bill-part having item-designations corresponding to the item-designations on the bill-part when the stub-part is folded along said vertical line into superimposed relation with the bill-part, and a record-part of the 125 bill-part having item-designations corresponding to the item-designations on the bill-part when the stub-part is folded along said vertical line into superimposed relation with the bill-part, and a record-part of the 130 bill-part having item-designations corresponding to the item-designations on the bill-part when the stub-part is folded along said vertical line into superimposed relation with the bill-part, and a record-part of the

joined at its bottom to the bottom of the bill-part along a transverse line of folding, and having an extension projecting beyond the bill-part coterminous with but unconnected to the adjacent bottom end of the stub-part, so that when the entry-sheet is flat the record-part will equal the combined widths of the bill-part and the stub-part, the record-part having thereon a transverse series of item-designations corresponding to the item-designations on the bill-part, but on the opposite side of the entry-sheet and vertically reversed when the entry-sheet is flat, the record-part also having on its said extension additional item-designations forming an extension of said transverse series, the item-designations on the record-part being brought into alignment with the corre-

sponding item designations on the bill-part and folded stub-part when the record-part is folded along said transverse line into superimposed relation with the bill-part and folded stub-part, the item-designating extension on the record-part projecting beyond the folded stub-part, so that said entry-sheet may be typed in its folded condition, thereby to type corresponding items upon the superimposed sheet-parts, and so that after such typing the record-part and stub-part may be separately detached from the bill-part along said lines of folding.

WILLIAM ASHLEY KELLY.
